US0D1013298S

(12) **United States Design Patent** (10) **Patent No.:** **US D1,013,298 S**
(45) **Date of Patent:** **** Jan. 30, 2024**

(54) **CLOTHING CARE MACHINE**

- (71) Applicant: **Samsung Electronics Co., Ltd.**, Suwon-si (KR)
- (72) Inventors: **Myunggyu Kim**, Suwon-si (KR); **Jinsook Park**, Suwon-si (KR); **Junkyo Lee**, Suwon-si (KR); **Euikyun Koh**, Suwon-si (KR)
- (73) Assignee: **SAMSUNG ELECTRONICS CO., LTD.**, Gyeonggi-Do (KR)
- (**) Term: **15 Years**
- (21) Appl. No.: **29/839,790**
- (22) Filed: **May 24, 2022**

(30) **Foreign Application Priority Data**

- Dec. 3, 2021 (KR) 30-2021-0058290
- (51) **LOC (14) Cl.** **15-05**
- (52) **U.S. Cl.** ..... **USPC D32/10**
- (58) **Field of Classification Search**
USPC D3/319; D6/560, 561, 662, 662.1, 663, D6/703, 703.2; D32/1, 6, 9, 10, 35
CPC .. D06F 58/10; D06F 2103/34; D06F 2105/40; D06F 2105/44; D06F 67/005; D06F 73/02; D06F 13/02

(57) **CLAIM**

The ornamental design for a clothing care machine, as shown and described.

DESCRIPTION

FIG. 1 is a front perspective view of a clothing care machine, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an enlarged view of the portion 8 encircled in FIG. 1.

The short dash-dash broken lines in the figures depict portions of the clothing care machine that form no part of the claimed design. The dot-dash broken lines encircling enlargement portions of the design form no part of the claimed design.

1 Claim, 8 Drawing Sheets
